United States Patent Office

Des. 178,661
Patented Sept. 4, 1956

178,661

WASTE RECEPTACLE

Clare J. Hoffman, Perrysburg, and William Carlton Green,
Cleveland, Ohio; said Green assignor to said Hoffman

Application November 8, 1954, Serial No. 33,000

Term of patent 14 years

(Cl. D58—17)

Fig. 1 is a perspective view of a waste receptacle showing our new design;

Fig. 2 is a side elevation thereof; and

Fig. 3 is a top plan view thereof.

We claim:

The ornamental design for a waste receptacle, substantially as shown.
